UNITED STATES PATENT OFFICE.

ADELBERT O. BENECKE, OF NEWARK, NEW JERSEY, ASSIGNOR TO AMERICAN INSTRUMENT COMPANY, OF NEWARK, NEW JERSEY, A CORPORATION OF NEW JERSEY.

RHEOSTAT.

No. 839,259.

Specification of Letters Patent.

Patented Dec. 25, 1906.

Application filed April 9, 1906. Serial No. 310,619.

To all whom it may concern:

Be it known that I, ADELBERT O. BENECKE, a resident of the city of Newark, county of Essex, and State of New Jersey, have invented 5 a new and useful Improvement in Rheostats, of which the following is a specification.

The construction of rheostats for laboratory and other purposes has hitherto been along certain lines which have rendered them objectionable for various reasons, among which may be stated that raised against the ordinary rheostat, wherein the resistances have to be cut in or cut out by means of one plug or a series of plugs, and in some cases the readings are not shown as direct, but the resultant readings must be arrived at by calculation. The single-plug rheostat is open to the objection that for step-by-step resistances up to ten ohms a 15 separate resistance-coil must be used for each step, thereby increasing the complication of the structure and rendering the same otherwise objectionable. In rheostats using a smaller number of resistance-coils additional plugs are used, requiring more or less manipulation of such plugs to obtain the necessary or required resistance.

The object of my invention is to overcome these objections and to produce a direct- 20 reading rheostat with a minimum number of resistance-coils.

I am able to utilize the principle of my invention either to produce series resistance or multiple resistance, and in the accompanying drawings, forming a part of this specification, I have shown the principle as applied to what I term a "series" rheostat and to a 25 multiple rheostat.

Figure 1 is a side elevation showing a series rheostat with the wiring for the same in diagram. Fig. 2 is an end elevation of the dial and index. Figs. 3, 4, 5, and 6 illustrate, respectively, side views of the several disks used in this construction. Fig. 7 illustrates one form of the means for securing the contact and insulation segments to the hub of the disk. Fig. 8 illustrates another manner, and Fig. 9 still another manner, of securing the segments to the disk. Fig. 10 illustrates a plan view of multiple rheostat. Fig. 11 illustrates a cross-section of the same, taken on line x of Fig. 10. Fig. 12 illustrates a plan view of the operating handle or

wheel and index-plate, and Figs. 13, 14, and 15 illustrate side views of the several disks used in the multiple rheostat.

Similar letters of reference refer to like parts of the specification and drawings.

In carrying out my invention I mount upon the insulating-base A the bearing-standards B B, carrying the shaft C at their upper extremities. Upon the shaft C at regular intervals I secure the disks D, E, F, and G. Secured to the end of the insulating base-plate A is the index-plate H, with the divisions from "1" to "0" marked upon its margin, the index-plate being concentric with the shaft C. At the end of the shaft C is the handle I, rigidly secured thereto, as is also the index-pointer K. The disks D, E, F, and G are composed of the center hubs L, as illustrated in Figs. 1 to 6. Said hubs may be made of metal or insulating material, as desired in this particular structure. Upon the peripheries of these hubs are mounted the metal segments M and the insulating-segments N, arranged as illustrated in Figs. 3, 4, 5, and 6, the disks being secured to the shaft in the relative positions illustrated for consecutive or step-by-step increases of resistance.

Secured to the base-plate A are the contact-springs O and P, as shown, the upper ends of these contact-pieces lying flat against the sides of the disk segments. These contact-springs are secured to the base-plate A by means of the binding-posts Q, as shown, said binding-posts passing through the plate and having binding-screws Q' at their opposite extremities. The leading-in wire R is secured to the first binding-post at the left, and the resistance-coils S of one ohm, S' of two ohms, S'' of two ohms, and S''' of five ohms are interposed between the pairs of binding-posts, as shown, for a purpose hereinafter to be described.

In the modification illustrated in Fig. 7 I have shown a plan for holding the segments M and N upon the hub L. In this case the segments are fitted against the periphery of the hub and held in position by means of the headed screws m, leaving a space n between adjacent segments, the screw itself being completely out of the path of the contact-springs P.

In the modification illustrated in Fig. 8 I

have illustrated another method of securing the segments to the hub L. In this case the brads or screws M pass directly through the segments and are secured into the hub L, 5 leaving the spaces n between the adjacent segments.

In the modification illustrated in Fig. 9 I show the disk as recessed on opposite sides adjacent to its periphery and insulating-segments inserted in said recesses. In this case 10 the segments may be held in position by means of rivets m, located outside of the path of the contact-springs P.

In all cases it is advisable to leave the 15 space n between adjacent segments so as to avoid the possibility of particles of the metallic segments or contact-springs which may become detached and adhere to the segments themselves from short-circuiting the device, 20 as would be the case if the adjacent segments were in close contact.

In operation where resistances are to be measured the rheostat is inserted in the circuit by connecting up the leading-in and the 25 leading-out wires, as shown, and then manipulating the knob or handle I to carry the index-pointer K around the face of the index-plate H. When the segments marked M are all between the contact-springs O and P, 30 as indicated in Fig. 1, the resistances S, S', S², and S³ are short-circuited and the current passes through the binding-post Q, the springs O and P, and out through the leading-out wire. In this case no resistance is 35 offered to the passage of the current. Upon turning the index-pointer, and with it the various disks, to a space marked "1" upon the index-plate all of the disks will be rotated; but it will be noted that the disk 40 marked "1" will have the insulating-segments I interposed between the first pair of contact-springs O and P, thereby directing the current through the resistance S, but short-circuiting all the other resistances. 45 Upon moving the index-pointer to the space marked "2" it will be noted that the disk marked "1" is short-circuited, while the current is directed through resistances S' and thereafter short-circuited through the rest of 50 the disks. In this manner all of the segments may be brought consecutively in the circuit up to "9" through the various combinations of the resistances of one, two, two, and five ohms. For example, the open-circuiting of "2" and "1" will give a resistance 55 of three ohms; of "2" and "2" will give four ohms; of "5" will give five ohms; of "5" and "1" will give six ohms; of "5" and "2" will give seven ohms; of "5," "2," and "1" 60 will give eight ohms; of "5," "2," and "2" will give nine ohms.

For higher resistances, separate units substantially of the same structure as that illustrated in Fig. 1 are provided in the device, 65 but with the exception that the resistances of

S, S', S², and S³ are increased to ten, twenty, twenty, and fifty, and for still higher resistances one hundred, two hundred, two hundred, and five hundred ohms are substituted. Thus the device may be arranged for measuring any resistance required by the addition 70 of units substantially as illustrated in Fig. 1, but with increased resistance-coils, as above indicated.

If desired, the resistance-coils S, S', S², and S³ may have different relative values—as, for example, one, two, three, and four ohms, respectively—and the relative location of the conducting and insulating segments correspondingly changed. I have chosen the values one, two, two, and five for the reason that their reciprocals which represent the relative conductivity of the coils may be expressed in even decimals, as one, .5, .5, and .2, while the reciprocals of any other set of four values to 85 produce the necessary results would give extended fractional values.

In the structure illustrated on Sheet 2 of the drawings I have shown what I term a "multiple" rheostat, wherein the same segmental-disk principle is involved. In this case I provide a supporting-frame A', upon which I mount the L-shaped conductor-plate B', said conductor-plate being secured to one of the upper members of the frame, as 90 shown. One end of this conductor-plate is provided with means B² for the purpose of securing bus-bars for connection with the leading-out wire. Superposed upon but insulated from the plate B' is the spring bearing-bar to which the leading-in wire is connected. Upon the upper face of the spring bearing-bar C' are the supporting-lugs C³, one or more in number, as shown, (the drawings showing three.) These lugs, as shown, 95 may be integral with the plate or separate therefrom and secured thereto in direct metallic connection. Secured to each of these lugs C³ upon their opposite sides are the contact-springs C⁴, bolted, as shown, to the lugs 100 and provided with the tension-bolts C⁵ for the purpose of adjusting the tension of the springs upon the disks, hereinafter to be described.

Upon the opposite side of the frame and 105 secured thereto, as shown, are the spring bearing-terminals D'. Upon these terminals D' are the lugs D² of substantially the same shape as lugs C³ upon the bar C'. The contact-springs D⁴, of substantially the same 110 shape, are secured to the lugs D² by the bolts D⁵, while the tension-bolts D⁶ regulate the bearing-pressure upon the disks hereinafter to be described. The several terminals D' are separately connected to the plate B' 115 through the resistances E', such resistances being in the following ratio: one ohm, .5 ohm, .5 ohm, and .2 ohm. I have shown diagrammatically in Fig. 1C these connecting resistances as E', E², E³, and E⁴. Mounted 120

in the bearing F' upon the upper part of the frame A' is the horizontal shaft G', as shown in Fig. 10. This shaft has secured at its forward extremity the hand-wheel H', to which is also secured to rotate therewith the index-plate I'. Upon the margin of the index-plate I' are the index divisions and figures from "1" to "10," inclusive. The stationary index-pointer K' is secured in any convenient manner either to the upper member of the frame A' or to the adjacent bearing F'.

Secured upon the shaft G' are the plain metallic disks L', the marginal faces of which lie between the contact-springs C⁴ of the plate C'. Mounted upon the shaft G' also are the segmental disks M', alternating with the disks L'. The segment-disks M' coöperate with the springs D³ of the L-shaped terminals D'. The segment-disks M' are made up, as shown in Figs. 11, 13, 14, and 15, with the metallic segments M² alternating with insulating-segments M³, preferably of hard rubber, spaces being left between the adjacent ends of the segments to avoid the short-circuiting, as heretofore described. The arrangement of the segments upon the several disks M' is clearly illustrated in Figs. 11, 13, 14, and 15 for step-by-step decreases in resistance, as heretofore described with respect to the structure illustrated in Fig. 1. The plain disks L' and the segment-disks M' are in electrical connection with the shaft G' and when in operation form part of the circuit.

A convenient form of resistance for multiple rheostats of this structure is illustrated in Fig. 11 and consists of a resistance-ribbon N', one end of which is connected to one of the plates D' and then carried in a zigzag manner over the insulating-plates O', as shown. It is to be understood in this connection that each of the plates D' is disconnected by means of a resistance-ribbon with the plate B', and the relative resistances of these several ribbons are in the ratio of one, .5, .5, and .2 ohm, so that the relative conductivity of the ribbons shall be in the ratio of one, two, two, and five. The ends of the ribbons N' are secured, respectively, to the plate B' and brackets D' by means of the clamping-plates P' and the screws Q', as shown in Fig. 11. I may also secure the ribbons to the insulating members O' by means of short dowel-pins O².

In operation, the rheostat is connected into a circuit, the leading-in wire being connected to the plate C' through the bus-bar connection C² and the leading-out wire being connected to the angle-plate B'. With the disks M' in the relative position illustrated in Figs. 11, 13, 14, and 15 it will be noted that the contact-springs D³ will all bear upon the insulating-segments, and consequently the circuit will be open. Upon moving the handle H', and with it the index-plate I', so that the pointer shall become adjacent to the index No. 1, it will be noted that the me-

tallic segment-plate M² will be brought in contact with the contact-springs D³. The current will then find passage through the plate C', the contact-springs C⁴, the disk L', segment M², contact-springs D³ through the resistance E⁴, to the plate B', and thence through the leading-out wire. In this case the resistances offered to the circuit is one ohm, and if the potential of the current is one volt the output will be one ampere. Upon moving the handle H' to the next division upon the index-plate the insulating-segment N² of disk No. 1 will be brought adjacent to the contact-springs D³, and the resistance-ribbon E⁴ will be cut out, while resistance E³ will be cut in. This resistance is .5 of an ohm. In this position it will be noted that all of the other disks at their insulating-segment are in contact with the springs D³. Therefore the current will pass only through the disk No. 2 and be cut out of all the other disks. The output under these conditions will be two amperes. For three amperes disks Nos. 1 and 2 will be cut in. For four amperes disks Nos. 2 and 3 will be cut in, and so on up to the point when the output shall be ten amperes.

In the multiple rheostat it will be noted that I have divided the disks M' into eleven divisions instead of ten, as in the series rheostat. However, if more units than one are used in the multiple rheostat, the successive units of resistance being correspondingly decreased, it will be unnecessary to divide the disks into more than ten parts; but for a single unit I prefer to divide into eleven divisions, so that the current may be cut out completely when the insulating-divisions of each of the disks shall be in contact with the springs D³.

While I have shown in Fig. 1 the index-plate as secured to the base A for this particular structure, I do not wish to be understood as confining that character of indicating means to that structure, as the index-plate can be secured to the shaft C, and the pointer K can be secured to the bracket B in substantially the same manner as the corresponding parts are shown in Fig. 10, or the structure of the index mechanism of Fig. 1 is equally adapted to the structure of Fig. 10. However, I prefer to use the stationary pointer and rotatable index-plate for each of the forms, as illustrated, and show that illustrated in Figs. 1 and 2 as alternative methods of securing the indicating means to the devices.

I claim—

1. In a rheostat, the combination of a rotary shaft, a plurality of disks secured upon said shaft, each of said disks being provided with an insulating peripheral segment and a conducting peripheral segment, contact-springs bearing upon opposite sides of said disks, a resistance-coil for each disk and

means for directing an electrical current either through the said conducting-segments or through the resistance-coil.

2. In a rheostat, the combination of a plurality of disks rigidly secured together to rotate, a plurality of insulating-segments, and a plurality of conducting-segments alternately disposed and secured to the peripheries of said disks, a resistance-coil adjacent to each disk, and means for directing a current of electricity either through a conducting-segment on a disk or through a resistance-coil.

3. In a rheostat, the combination of a rotatable shaft, a disk mounted on said shaft, a plurality of alternately-disposed conducting and insulating peripheral segments secured to said disk, contact-springs mounted to bear upon opposite faces of said peripheral segments, a resistance-coil adjacent to said disk, and means for connecting up said parts in an electrical circuit.

4. In a rheostat, the combination of a rotatable disk, a plurality of alternately-disposed conducting and insulating peripheral segments secured to said disks, and contact-springs mounted to bear upon opposite faces of said peripheral segments with a resistance-coil and means for connecting up said parts in an electrical circuit.

5. A rheostat, comprising a series of rotatable disks rigidly secured to a shaft, alternately-disposed conducting and insulating segments forming the peripheries of said disks, resistance-coils of differing capacities located respectively adjacent to said disks and electrical connections for sending a current either through said conducting-segments or through said resistance-coils.

6. A rheostat comprising a rotatable shaft, a series of disks spaced apart and rigidly secured to said shaft, peripheral segments secured to said disk, said segments being composed of conducting material and non-conducting material alternately disposed, a pair of contact-springs embracing the edges of the peripheral segments upon each disk, a resistance-coil in electrical connection at one end with each pair of contact-springs, and at the other with a common terminal, and means for directing an electric current through one or more of said disks and to said common terminal by way of one or more of said conducting-segments, contact-springs and resistance-coils.

7. A rheostat comprising in combination, a rotatable shaft having secured thereon, a conducting-disk, and a series of disks having alternately-disposed peripheral segments of conducting and of insulating material, the adjacent ends of said segments being spaced apart, a leading-in terminal having mounted thereon a pair of contact-springs, said springs embracing the periphery of said conducting-disk, a series of separate pairs of contact-springs, each pair embracing the periphery of

one of said segment-disks, a leading-out terminal and a separate resistance-coil in electrical connection with each pair of said separate pairs of contact-springs, and said common terminal.

8. In a rheostat, the combination of a rotary shaft, a plurality of disks secured upon said shaft, each of said disks being provided with an insulating peripheral segment and a conducting peripheral segment, contact-springs bearing upon opposite sides of said disks, a resistance-coil for each disk, means for directing an electrical current either through the said conducting segments or through the resistance-coil, and an index dial and pointer secured to said rheostat for indicating the resistance offered to the passage of the current.

9. In a rheostat, the combination of a plurality of disks rigidly secured together to rotate, a plurality of insulating-segments and a plurality of conducting-segments alternately disposed and secured to the peripheries of said disks, a resistance-coil adjacent to each disk, means for directing a current of electricity either through a conducting-segment on a disk or through a resistance-coil, and an index dial and pointer secured to said rheostat for indicating the resistance offered to the passage of the current.

10. In a rheostat, the combination of a rotatable shaft, a disk mounted on said shaft, a plurality of alternately-disposed conducting and insulating peripheral segments secured to said disk, contact-springs mounted to bear upon opposite faces of said peripheral segments, a resistance-coil adjacent to said disk, means for connecting up said parts in an electrical circuit, and means for indicating the resistance offered to the passage of the current.

11. In a rheostat, the combination of a rotatable disk, a plurality of alternately-disposed conducting and insulating peripheral segments secured to said disks, and contact-springs mounted to bear upon opposite faces of said peripheral segments with a resistance-coil, means for connecting up said parts in an electrical circuit, and means for indicating the resistance offered to the passage of the current.

12. A rheostat, comprising a series of rotatable disks rigidly secured to a shaft, alternately-disposed conducting and insulating segments forming the peripheries of said disks, resistance-coils of differing capacities located respectively adjacent to said disks, electrical connections for sending a current either through said conducting-segments or through said resistance-coils, and means for indicating the resistance offered to the passage of the current.

13. A rheostat, comprising a rotatable shaft, a series of disks spaced apart and rigidly secured to said shaft, peripheral seg-

ments secured to said disk, said segments being composed of conducting material and non-conducting material alternately disposed, a pair of contact-springs embracing the edges of the peripheral segments upon each disk, a resistance-coil in electrical connection to one end with each pair of contact-springs, and at the other with a common terminal, means for directing an electric current through one or more of said disks and to said common terminal by way of one or more of said conducting-segments, contact-springs and resistance-coils, and an index-plate secured to said shaft, said plate having indices upon its margin, and a fixed index-pointer located adjacent to the margin of said plate.

14. A rheostat, comprising in combination, a rotatable shaft having secured thereon a conducting-disk, and a series of disks having alternately-disposed peripheral segments of conducting and of insulating material, the

adjacent ends of said segments being spaced apart, a leading-in terminal having mounted thereon a pair of contact-springs, said springs embracing the periphery of said conducting-disk, a series of separate pairs of contact-springs, each pair embracing the periphery of one of said segment-disks, a leading-out terminal, a separate resistance-coil in electrical connection with each pair of said separate pairs of contact-springs, and an index-plate secured to said shaft, said plate having indices upon its margin, and a fixed index-pointer located adjacent to the margin of said plate.
